(57) **CLAIM**

The ornamental design for a weightlifting assembly as shown and described.

DESCRIPTION

FIG. 1 is a top, front, left perspective view of one embodiment of a weightlifting assembly showing our new design; FIG. 2 is a left side view thereof;

FIG. 3 is a right side view thereof;

FIG. 4 is a front view thereof;

FIG. 5 is a rear view thereof;

FIG. 6 is a top view thereof;

FIG. 7 is a bottom view thereof;

FIG. 8 is a top, rear, right perspective view thereof; and, FIG. 9 is an enlarged view of the outlined portion labeled as FIG. 9 in FIG. 8.

The broken lines immediately adjacent to the shaded area define the bounds of the claimed design and form no part thereof. The broken lines depicting the remainder of the weightlifting assembly form no part of the claimed design. The uneven-length broken lines indicate boundaries of areas of enlarged views and form no part of the claimed design.
